Des. 183,973
Patented Nov. 25, 1958

183,973

LAMP SHADE

Mary J. Navratil, San Francisco, Calif.

Application December 6, 1957, Serial No. 48,817

Term of patent 14 years

(Cl. D48—16)

Fig. 1.

Fig. 2.

The broken line showing in Figures 1 and 2 is for the purpose of illustration only.

I claim:

The ornamental design for a lamp shade, as shown and described.
